PRINTING PRESS AND SHEET-CONTROLLING MECHANISM THEREFOR

Morris Lipton, Rutherford, N. J., assignor to General Printing Ink Corporation, New York, N. Y., a corporation of Delaware

Application January 10, 1939, Serial No. 250,115

17 Claims. (Cl. 271—46)

My invention relates to a printing press and, further, the invention relates to sheet-controlling mechanism for a printing press or the like.

In accordance with my invention, a novel mechanism is provided for controlling the application of a dampening medium to the printing press cylinder assembly.

My invention has further reference to novel mechanism for feeding sheets along a path and, in addition, the invention relates to novel arrangements for adjusting the position of sheets transversely of said path as they are moved therewith by the feeding mechanism.

My invention resides in the printing press features, sheet-controlling mechanism, combinations and arrangements of the character herein-after described and claimed.

For an understanding of my invention and for an illustration of some of the many forms thereof, reference is to be had to the accompanying drawings, in which:

Figure 1 is a perspective view, partly broken away, showing a printing press and associated sheet-controlling mechanism as constructed in accordance with my invention;

Fig. 2 is a longitudinal vertical sectional view, partly in elevation, showing features of my novel sheet-feeding mechanism;

Fig. 2a is a longitudinal vertical sectional view, partly in elevation, showing a part of the mechanism of Fig. 2;

Fig. 3 is a transverse vertical sectional view, partly in elevation, taken approximately on the line 3—3 of Fig. 2 looking in the direction of the arrows;

Fig. 3a is a vertical sectional view, partly in elevation, taken on the line 3a—3a of Fig. 3;

Fig. 3b is an elevational view, partly in section, showing one of the pusher finger assemblies;

Fig. 4 is a plan view, partly in section, showing apparatus at and adjacent the discharge zone of the sheet-feeding mechanism;

Fig. 4a is a vertical sectional view, partly in elevation, taken on the line 4a—4a of Fig. 4 looking in the direction of the arrows;

Fig. 5 is a plan view showing apparatus at and adjacent the entrance zone of the sheet-feeding mechanism;

Fig. 6 is an elevational view showing a driving connection for the side gauges;

Fig. 7 is a plan view, partly broken away, showing a form of a side gauge;

Fig. 7a is an enlarged, vertical sectional view, partly in elevation, showing a part of the side gauge illustrated in Fig. 7;

Fig. 8 is a plan view illustrating control means for the side gauges;

Fig. 9 is a vertical sectional view, partly in elevation, and is taken on the line 9—9 of Fig. 7;

Fig. 10 is a plan view illustrating side gauges of another form;

Fig. 11 is a vertical sectional view, partly in elevation, showing the mechanism of Fig. 10;

Fig. 11a is a transverse, vertical sectional view, partly in elevation, taken on either of the lines 11a—11a of Fig. 11.

Fig. 12 is a vertical sectional view, partly in elevation, showing mechanism for controlling the application of a dampening medium to the printing press cylinder assembly;

Fig. 12a is a transverse vertical sectional view, partly in elevation, taken on the line 12—12a of Fig. 12;

Fig. 13 is an elevational view, partly in section, showing a part of the mechanism of Figs. 12 and 12a;

Fig. 14 is a plan view, partly in section, showing a part of the mechanism of Figs. 12 and 12a; and

Fig. 15 is a plan view, partly in section, showing a part of the control mechanism of Figs. 12 and 12a.

Referring to Fig. 1, B represents a base adapted to rest upon the floor or other suitable supporting surface. Upstanding from the base B are a plurality of spaced side frames 1 which extend longitudinally of said base B and are suitably secured thereto.

At one side of the base B, an upstanding bearing bracket 2, Fig. 4, is suitably secured thereto, this bearing bracket 2 having journaled therein a horizontal shaft 3 to which is secured for rotatable movement therewith a gear wheel 4, a pulley 5 and a hand wheel 5a, Fig. 1, the latter

serving in the usual manner as a fly wheel and for manual control purposes when placing the printing press in condition for operation. The pulley 5 is driven by a belt operated by any suitable source of power, not shown, and the gear wheel 4 meshes with and drives a gear wheel 7 fixed to one end of a horizontal shaft 8, Figs. 1 and 4, extending transversely with respect to the base B and journaled in bearing brackets 9 upstanding therefrom.

Secured to the shaft 8, Figs. 1 and 4, is a gear wheel 10 which meshes with and drives a gear wheel 11 rotatable on a horizontal stub shaft 12 projecting inwardly from one of the side frames 13 for the printing press P, the side frames 13 being disposed in alignment with the respective

55

side frames 1. The gear wheel 11 meshes with and drives a gear wheel 14 which is secured to and rotatable with the impression cylinder 15 of the printing press, said gear wheel 14 meshing with and driving another gear wheel 16 rotatable with the blanket cylinder 17 of said printing press, the impression cylinder 15 and the blanket cylinder 17 being suitably journaled in the aforesaid side frames 13.

Although not illustrated in detail herein, it is to be understood that the printing press P may be of any conventional type, said press P, in the example shown although not necessarily, being an offset press. That is, the rubber blanket on the cylinder 17 successively receives inked impressions from another cylinder, not shown, and transfers these impressions in succession to the respective sheets of material as they are passed in timed relation and in succession from right to left, Fig. 1, between the cylinders 15 and 17.

By the train of gear connections described above, power is transmitted from the pulley 5 to the gear wheel 11 which, in turn, delivers power to the various power-receiving parts of the printing press.

The impression cylinder 15, as it rotates, by suitable conventional means, not shown, causes oscillation of its transverse shaft 15a whereby the gripper fingers 15b thereon are closed in timed relation to grip a sheet passed thereto by the hereinbefore described sheet-feeding mechanism, said gripper fingers 15b being subsequently opened when the sheet is to be released.

The hereinbefore described side frames 1 are secured in spaced, frame-forming relation by suitable means which includes a plurality of tie rods 20 horizontally fixed in said side frames 1, Figs. 4 and 5. Journaled in said side frames 1 are a plurality of horizontal shafts 21, 21a and 21b utilizable as hereinafter described. As shown in Fig. 4, a pair of spaced bearing supports 22 are suitably secured in fixed position to an adjacent pair of the aforesaid tie rods 20. Each of these bearing supports comprises a pair of horizontally extending arms 22a.

Journalized in the arms 22a and in that side frame 1 toward the left, Fig. 4, is a horizontal shaft 23. Freely rotatable on the shaft 23 is a sprocket wheel 24 driven by an endless sprocket chain 25 driven, in turn, by a sprocket wheel 26 rotatable on the aforesaid stub shaft 12 and suitably secured to the gear wheel 11 for rotatable movement therewith.

Suitably secured to the sprocket wheel 24, as by screws 27, Fig. 4, is a disk 28 freely rotatable on said shaft 23. Adjacent the disk 28, the shaft 23 has a gear wheel 29 secured thereto for rotatable movement therewith, Fig. 4a, the gear wheel 29 meshing with three outer gear wheels 30, 31 and 32 rotatable on the respective stub shafts 33, the stub shafts 33 being secured to the aforesaid disk 28 and projecting horizontally therefrom. As clearly appears from Fig. 4a, the stub shafts 33 are disposed circumferentially around the shaft 23 and are spaced one hundred and twenty degrees apart. The gear wheels 30, 31 and 32 also mesh with the internal threads on a ring gear 34 having a web section 34a terminating in a hub secured to the hub of the aforesaid gear wheel 29. The ring gear 34 has a casing member 35 suitably secured thereto, as by the bolts 36, Fig. 4, this casing member 35 having a web section 35a terminating in a hub mounted on and movable with respect to the hub of the aforesaid disk 28. As indicated in Fig. 4, the ring gear 34 to-

gether with its web section 34a and the casing member 35 together with its web section 35a form a tight housing enclosing the gear wheels 29, 30, 31 and 32, this housing being thus provided so that a supply of grease may be disposed therein for lubricating purposes.

Secured to housing 34 for rotatable movement therewith is a worm gear 37 which is disposed immediately adjacent the exterior face of the ring gear 34, Fig. 4. Meshing with the worm gear 37 is a worm 38 secured to one end of a shaft 39 for rotatable movement therewith, the shaft 39 being mounted in spaced bearings 40 secured to the interior surface of the adjacent side frame 1. The shaft 39, at its end removed from the worm 38, has a worm 43 and a gear wheel 42 secured thereto for rotatable movement therewith.

The worm 43 meshes with a worm wheel 41 secured to and rotatable with one end of the aforesaid shaft 21 which, at its other end, has secured thereto a gear wheel 44 which meshes with a gear wheel 45 rotatable on a stub shaft 46 horizontally disposed in the adjacent side frame 1; the shaft 46, exteriorly of said last named side frame 1, carrying a dial 47 with which coacts a fixed pointer 48.

The aforesaid gear wheel 42 meshes with a gear wheel 49 secured to and rotatable with one end of the aforesaid shaft 21a which, at its other end, carries a hand wheel 50 disposed exteriorly of the adjacent side frame 1.

Referring to Fig. 4, the aforesaid shaft 23 has secured thereto for rotatable movement therewith a pair of spaced gear wheels 51, 51a which are disposed between the respective pairs of arms 22a. The gear wheels 51, 51a are disposed in meshing relation with a second pair of spaced gear wheels 52, 52a secured to and rotatable with the respective shafts 53 which are journaled at the extreme ends of the respective pairs of arms 22a. Further, the shafts 53 have secured thereto for rotatable movement therewith the respective sprocket wheels 54, 54a utilizable as hereinafter described.

Suitably fixed to that tie rod 20 most removed from the printing press P are a plurality of bearing members 55, 55a, Fig. 5, in which a horizontal shaft 56 is journaled. This shaft 56 carries a pair of spaced sprocket wheels 57, 57a disposed in longitudinal alinement with the respective sprocket wheels 54, 54a above described.

The sets of longitudinally alined sprocket wheels 54, 57 and 54a, 57a receive the respective endless sprocket chains 58, 58a, the two chains being disposed in parallel relation and the upper spans thereof being horizontally alined for the purpose hereinafter described.

Each sprocket chain carries a pair of bracket arms 59 spaced from each other by equal sprocket chain lengths, said bracket arms 59 being suitably secured to the respective sprocket chains by the respective bolts 60, Fig. 3. The bracket arms 59 are alined in pairs transversely and each of said bracket arms 59 carries a horizontally extending bolt 61, each bolt 61 serving as a support for a roller 62. Further, each bolt of each pair of transversely alined bolts 61 supports a laterally extending arm 63a of a horizontal cross bar 63.

As illustrated in Figs. 3 and 4, a pair of spaced blocks 64 are shown as secured in fixed position to that tie rod 20 which is nearest the printing press P. As indicated in Fig. 5, a similar pair of spaced blocks 65 are shown as secured in fixed position to that tie rod 20 which is most

removed from said printing press P. The blocks 64 and 65 are alined in pairs longitudinally of the sheet-feeding mechanism.

Secured by bolts 66 to the upper outside section of the block 64 and by bolts 67 to the upper outside section of the block 65 is a supporting bar 68 which extends longitudinally of the sheet-feeding mechanism and serves as a support for the upper horizontal span of the sprocket chain 58. The upper horizontal span of the sprocket chain 58a is similarly supported by duplicate members to which corresponding reference numerals have been applied with the reference letter *a* added in each instance.

Secured by bolts 69 to the lower section of the block 64 and by bolts 70 to the lower section of the block 65 is an angle member 71 which extends longitudinally of the sheet-feeding mechanism and has secured to the lower surface thereof a supporting bar 72 for the lower horizontal span of the sprocket chain 58. The lower horizontal span of the sprocket chain 58a is similarly supported by duplicate members to which corresponding reference numerals have been applied with the reference letter *a* added in each instance.

Secured by bolts 73 to the upper inside section of the block 64 and by bolts 74 to the upper inside section of the block 65 is a member 75 having an angle section with which the rollers 62 carried by the chain 58 are adapted to engage. Similarly, the rollers 62 carried by the chain 58a are adapted to engage a corresponding angle section supported in a corresponding manner, the members last noted having applied thereto corresponding reference numerals with the reference letter *a* added in each instance.

Extending longitudinally of the machine is a web member 76 which, as shown in Fig. 3, is disposed in a vertical plane. As indicated on the drawings, all of the tie rods 29 and the shafts 23, 21, 21a, 56 extend through this web member 76. As illustrated in Figs. 3 and 4, said web member 76 may comprise hubs 76a through which two or more of the tie members 29 extend, respectively, these hubs and tie members being pinned or otherwise suitably secured together as shown.

Suitably secured to each cross bar 63, as by a bolt 77, Figs. 3 and 3a, is a bracket member 78 which, at its lower end, carries a pivoted lever 79. Secured to one end of the lever 79 is a member 80 which is disposed loosely in spaced bearing sections formed in an upstanding section of said bracket member 78. A nut member 81 prevents casual disengagement of the member 80 from said bearing sections and maintains under compression a helical spring 82 which is disposed around said member 80, this spring 82 constantly biasing the other end of the lever 79 toward the cross bar 63. The last named end of each lever 79 carries a freely rotatable roller 83 which is adapted to engage a laterally extending section 76b of the web 76, this section 76b extending substantially throughout the entire length of said web member 76 at the upper surface thereof, Fig. 2a.

Suitably secured to each cross bar 63, as by the bolts 84, Fig. 3, is an inclined member 85 terminating in a hub which supports a horizontally disposed axle 86 upon which a roller 87 is freely rotatable, this roller 87 being utilizable as hereinafter described.

As clearly shown in Figs. 2a and 3, the aforesaid web member 76 is shaped to form a groove

76c which extends around the ends thereof and along the lower surface thereof. This groove 76c is traversed in procession by the above described rollers 87 and these rollers, just after they leave said groove 76c at the exit end 76d thereof, Fig. 2a, pass downwardly over an inclined section 76e whereby a tilting action is imparted to the cross bars 63 in succession. This is a feature of the invention which will subsequently be described in a detailed manner.

The above described web member 76, at the upper surface thereof and approximately midway between the ends thereof, carries a member 88 which extends longitudinally thereof, Fig. 15, 2, the upper surface of this member 88, at the end thereof toward the printing press, comprising an upwardly inclined section 88a, a substantially horizontal section 88b and a downwardly inclined section 88c. In accordance with the invention, the member 88 is adapted for adjustment longitudinally with respect to the web member 76 and, to this end, said member 88 may be movable freely along a channel formed by a surface of the web member 76 and an adjacent angle member 89 secured to said web member 76 by bolts 90, Fig. 3. In order to effect positive adjustment of the member 88, the lower surface thereof may be formed with rack teeth with which mesh a gear wheel 91 secured to and rotatable with the above described shaft 21.

In accordance with the invention and as shown particularly in Fig. 3b, each cross bar 63 carries sheet feeding means which, as herein illustrated, is exemplified by a pair of spaced pusher finger assemblies. Each of the assemblies comprises a bracket 92 having a channel section within which the associated bar 63 is received, each bracket 92 being retained by a set screw 93 in a desired adjusted position longitudinally of said bar 63. Further, each bracket 92 comprises a pair of upstanding arms through which extends a pin 94 on which is freely pivoted a member 95 having secured thereto as by rivets, or equivalent, a finger or finger plate 96. Pivoted to the member 95 is a rod 97 which extends freely through a passage formed in an extension 92b of the bracket 92. The rod 97 carries a helical spring 98 which is confined between said extension 92b and a nut 99 threaded to the end of said rod 97 whereby the finger 96 is biased in a clockwise direction, Fig. 3b.

As indicated in Fig. 2, a member 100 extends transversely between the side frames 1 at the ends thereof remote from the printing cylinders. This member 100 is bolted or otherwise suitably secured to said side frames 1 and it serves as a brace with respect thereto. In addition, the member 100 serves as a support for the adjacent ends of a plurality of slats 101 which extend longitudinally of the machine and terminate immediately adjacent the entrance to the printing zone as defined by the impression cylinder 15 and blanket cylinder 17, said slats 101 being suitably supported adjacent said zone as, for example, by a member 102 which extends transversely between the aforesaid side frames 1 and is suitably secured in fixed position, Fig. 10.

For preliminary feeding of individual sheets S of material along the slats 101 toward the printing zone, there may be utilized an arrangement of any suitable character. Thus, as herein shown in Figs. 1, 2 and 5, the aforesaid shafts 56 and 21b have the respective sprocket wheels 103 and 104 secured thereto for rotatable movement there-

with, these sprocket wheels carrying the sprocket chain 105.

Mounted for free oscillatory movement on the shaft 21b are a plurality of hubs 106, each hub 106 being confined in its proper position by the hub of a sprocket wheel 107 and a collar 108 secured to said shaft 21b. Formed integrally with each hub 106 are a pair of angularly related arms 109, Fig. 5, the sets of arms being disposed in alignment transversely of the machine.

Each arm 109 terminates in a hub 110 which forms a bearing for a shaft 111, and each shaft 111, at the respective opposite ends thereof, carries a magnetic feed roller 112 and a sprocket wheel 113. The sprocket wheels 113 are disposed in alignment longitudinally of the machine with the respective sprocket wheels 107, and a sprocket chain 114 is trained over each set of longitudinally aligned sprocket wheels 107 and 113.

The arm 109 may be bifurcated as shown at the left of Fig. 5 for the reception of a pin which supports a roller 115. Coactable with the roller 115 is a cam 116, that cam 116 being fixed to and movable with a shaft 117 mounted for oscillatory movement in the side frames 1. The shaft 117 has secured thereto for oscillatory movement therewith a pair of spaced collars 118 and each collar 118 carries an arcuate finger 119, these fingers 119 being disposed in alignment, longitudinally of the machine, and beneath the aforesaid magnetic feed rollers 112, respectively.

Secured to the shaft 117 for oscillatory movement therewith is a downwardly extending lever arm 120, Fig. 2, to the lower end of which is pivoted one end of a link 121 pivoted at its other end to the upper end of an arm 122, the lower end of which is pivoted to a bracket 123 secured to the aforesaid base B. The arm 122 supports a roller 124 which coacts with a cam 125 secured to and rotatable with the aforesaid shaft 8. The roller 124 should be biased against the cam 125 and, to this end, one end of a spring 126 may be secured to the aforesaid arm 120, the other end of this spring being suitably anchored so that the arm 120 is biased in a clockwise direction, Fig. 2.

Referring to Fig. 1, the hereinbefore described base B is shown as comprising a pair of spaced extensions b which support the respective standards 128, the latter, in turn, supporting the vertically adjustable brackets 129 which are adapted to detachably support a platform 130 carrying a stack of the sheets S which are to be passed through the printing press. In lieu of the construction just described, it will be understood that the sheets of material which are to receive the printing impressions may be supplied in any other suitable manner to the entrance zone of the sheet-feeding mechanism.

The operation of the sheet-feeding mechanism is as follows:

As hereinbefore pointed out, power is applied to the pulley 5 to operate the gear wheel 11 and, as stated, the sprocket wheel 26 is secured to said gear wheel 11 for rotatable movement therewith. The sprocket wheel 26 operates the sprocket chain 25 and the latter, in turn, effects rotation of the sprocket wheel 24 and the disk 28. The latter rotates the gear wheels 30, 31 and 32 which, in turn, rotate the gear wheel 29 whereby the shaft 23 is rotated in a counter-clockwise direction, Fig. 2. From the shaft 23, power is obtained for rotating the sprocket chains 58, 58a so that the upper spans thereof move in a direction from right to left, Fig. 2, such power being supplied to

the respective sprocket chains 58, 58a by the sets of gear wheels 51, 52 and 51a, 52a.

As the sprocket chains 58, 58a move as described, the upper spans thereof rest upon and are restrained from sagging movement by the respective supporting bars 68, 68a, Fig. 3. Similarly, the lower spans of the respective sprocket chains 58, 58a, as they move from left to right, Fig. 2, are supported by and are restrained from sagging movement by the respective supporting bars 72, 72a, Fig. 3.

The rollers 62 which were described as secured to the respective sprocket chains 58, 58a coact with and ride beneath the respective angle members 75 as the upper sprocket chain spans move from right to left, Fig. 2. In this way, the chains 58, 58a are prevented from vibrating or moving upwardly in an undesired manner.

The roller 87 of each cross bar 63, as it moves through its cycle, engages in succession the inclined section 76c of the web member 76 and the inclined sections 88a, 88b, 88c of the member 88, said roller 87 thereafter completing its cycle by traversing the groove 76c of the web member 76.

The rollers 83 move with their respective cross bars 63 as the latter pass from right to left, Fig. 2. In so doing, these rollers coact with and ride beneath the above described lateral extending section 76b of the web member 76. As a result, the cross bars 63 are prevented from tilting in an unintended manner when the sheets S are fed toward the printing zone.

The hereinbefore described shaft 56 receives power from the sprocket chains 58, 58a and this shaft 56, in turn and by the sprocket chain 105, delivers power to the shaft 21b. The shaft 21b rotates in a counter-clockwise direction, Fig. 2, and, by the sprocket chains 114, causes the respective magnetic feed rollers 112 to rotate in a counter-clockwise direction, Fig. 2.

The hereinbefore described shaft 117 is periodically oscillated under the control of cam 125 and the associated connections. As a result, the fingers 119 are periodically elevated until their upper ends are slightly above the upper surface of the slats 101. Likewise, under the control of the shaft 117, the magnetic feed rollers 112 are oscillated so that for an interval, the upper surface of each feed roller 112 is substantially flush with the upper surface of the slats 101, Fig. 2, while for another interval, the upper surface of said feed rollers 112 are below said upper surface of the slats 101.

Assuming that the fingers 119 are in elevated position, the operator removes the topmost sheet S from the stack of sheets shown in Fig. 1 and manually positions the same on the slats 101, at the entrance zone thereof, with the forward edge of said sheet S in engagement with the fingers 119 and immediately above the feed rollers 112.

Soon after this has been done, the shaft 117 moves counter-clockwise, Fig. 2, under the control of the cam 125 and, just as the fingers 119 are removed from engagement with said forward edge of the sheet S, the feed rollers 112, under the control of the respective cams 116, are moved into engagement with the lower surface thereof. These rollers 112 rotate constantly in a counter-clockwise direction, Fig. 2, and, therefore, by magnetic clutching action of said sheet S, the latter is moved in a direction from right to left, Fig. 2, along the slats 101.

Just as or soon after the feed rollers 112 have completed the movement of the sheet S toward the left, Fig. 2, the fingers 96 of the respective

pusher assemblies engage the rear edge of said sheet S and initiate further movement thereof toward the printing zone. Just as the fingers 96 thus engage the sheet S, the roller 87 engages the inclined section 76e of the web member 76 with the result that the cross bar 63 is tilted slightly toward the stack of sheets at the rear of the machine. Accordingly, the shock resulting from engagement of the fingers with the sheet S is decreased. This is desirable because, during high-speed operation, sudden impact on the rear edge of the sheet is apt to produce some undesired lateral movement thereof.

The upper spans of the sprocket chains 58, 58a move continuously from right to left, Fig. 2, and, therefore, under the control of the fingers 96, the sheet S is advanced along the slats 101 toward the printing zone.

The impression cylinder 15, of course, rotates continuously. The timing is such that the gripper fingers 15b of this impression cylinder are open and in a position to receive the forward edge of the sheet S as the latter is delivered into the printing zone. Just as said forward edge of the sheet S thus comes adjacent the fingers 15b, the aforesaid roller 87 engages the inclined section 88a of the member 88 with the result that the cross bar 63 is tilted slightly toward the printing press P. Accordingly, the speed of the sheet S is accelerated momentarily and, therefore, quickly advanced so that the front edge thereof comes into engagement with the usual stop members, not shown, carried by the impression cylinder 15. As these stop members are thus engaged by the sheet S, the finger 96 of each pusher mechanism moves clockwise, Fig. 2, against the associated spring 98, the springs 98 being provided to compensate for such slight differences as may occur with respect to the lengths of individual sheets. Soon thereafter, the roller 87 comes into engagement with the horizontal section 88b of the member 88 with the result that the cross bar 63 resumes its normal position. At this time, the sheet S is being drawn by the impression cylinder 15 and pushed by the fingers 96. This action continues until at about the time that the printing operation starts whereupon the roller 87 passes downwardly along the inclined section 88c of said member 88 with the result that the cross bar 63 is tilted slightly toward the rear of the machine. As a result, the sheet S, now entirely under the control of the impression cylinder 15, is drawn away from the fingers 96.

As the cross bar assembly continues its journey, the roller 87 associated therewith enters and passes through the groove 76c, the wall surfaces of which exert a steadyng effect on said cross bar assembly.

As hereinbefore stated, the sprocket chains 58, 58a carry a pair of the cross bar assemblies which are equally spaced from each other. As soon as one pusher bar assembly has completed its intended function of delivering a sheet S to the printing cylinders, the other pusher bar assembly is approaching the feed rollers 112 from which it removes the next sheet S and feeds the same to the printing zone in the manner hereinbefore described. Thus, the sheets are delivered in succession to the printing press P.

It will be understood that, when the sheet-feeding mechanism operates as described above, all of the sheets S are necessarily of substantially the same length. This follows because the distance between the cam sections 88a, 88b and

88c of the member 88 and the entrance to the printing cylinders 15, 17 remains constant, and the same is true with respect to the distance between the point at which the fingers 96 become disengaged from the rear surface of each sheet S and said entrance to the printing cylinders 15, 17. In accordance with my invention, by a simple manual operation, the mechanism may be adjusted so that sheets of different lengths may be fed to the printing cylinders.

To this end, if sheets S of a longer length are to be fed by the pusher assemblies, the operator may rotate the hand wheel 50 in the proper direction whereby the shaft 21a, through the gear wheels 49 and 42, effects rotation of the hereinbefore described shaft 39.

As one result of this operation, the shaft 21 is rotated by virtue of the driving connection afforded by the worm 43 and worm wheel 41. The shaft 21 carries the hereinbefore described gear wheel 91, Fig. 2, which meshes with the rack teeth on the member 88 and, when this gear wheel 91 is rotated in a clockwise direction, Fig. 2, the member 88 is moved from left to right, Fig. 2. Accordingly, the position of the inclined sections 88a, 88b and 88c of said member 88 is changed so that they perform their described functions a longer distance from the entrance to the printing cylinders 15, 17 than was the case with the arrangement previously described.

As another result of this operation, the shaft 29, by the worm 38 and worm gear 37, causes rotation of the shaft 23 whereby a step of rotative movement is imparted to the sprocket chains 58, 58a. In so doing, the upper cross bar 63 is moved from left to right, Fig. 2, the same distance that the member 88 was moved in the same direction as described above. Obviously, the lower cross bar 63, in response to the above noted rotative movement of the sprocket chains 58, 58a is moved a corresponding distance from right to left, Fig. 2. The sprocket chains 58, 58a are timed with the printing press cylinders and, therefore, it is necessary to adjust the position of said sprocket chains in the manner described when sheets S of longer length are to be fed by the pusher assemblies.

It will be understood, if sheets S of a shorter length are to be fed by the pusher assemblies, the operator merely rotates the hand wheel 50 in a direction the reverse of that described above.

When the shaft 23 is rotated under control of the hand wheel 50 as described above, the gear wheel 29 coacts with and moves the gear wheels 30, 31 and 32 with respect to the ring gear 34, Fig. 4a. This action has no effect on the power transmitting mechanism.

Accordingly, in view of the foregoing, it follows that the operator, by consulting the previously calibrated dial 47 and adjusting the same with respect to the pointer 48, may shift the sheet-feeding mechanism so that it will feed sheets of different length as desired. In a highly important sense, this adjusting operation may be performed while the printing press, the sheet-feeding mechanism and associated parts are operating at full or fractional speed. Accordingly, by my invention, a shut-down is not required when the printing operation is to be effected on sheets of different sizes. Time and labor are thereby saved.

It is well known in the art that the sheets S should follow the same identical course as they pass between the impression cylinder 17 and the

blanket cylinder 15 of the printing press P. The hereinbefore described pusher fingers 96 cause the sheets S to follow a course which is approximately correct while they are passing toward said printing cylinders. However, in order that said sheets S may be located precisely on the intended course just prior to the time that they enter between the printing cylinders, I have provided a novel form of side gauge mechanism of the character hereinafter described.

Thus, by reference to Figs. 4 and 9, a bar 131, positioned adjacent the printing cylinders, is shown as extending horizontally across the machine and is suitably secured to the aforesaid side frames 13. Secured to the bar 131 by screws 132 are a plurality of brackets 133 having upwardly extending arms to which a pair of spaced, horizontal tracks 134 are bolted or otherwise suitably secured, these tracks 134 being disposed at the respective opposite sides of the machine as shown in Fig. 4.

Associated with each track 134 is a carriage 135 slidably retained to its associated track 134 by a plate 135a suitably secured to the bottom of said carriage 135, as by the bolts 136. Each carriage 135 has a casing 137 suitably secured thereto, as by the bolts 138, the casings 137 being disposed in facing relation transversely of the machine, Fig. 4.

Threaded into the opposite ends of each casing 137 are the respective sleeve nuts 139, 140 provided, respectively, with longitudinally aligned passages through which a slide member 141 freely extends, said slide member 141 comprising a disk 142 disposed within the associated casing 137. Each slide member 141 has a helical spring 143 disposed therearound, one end of this helical spring 143 engaging the inner end of the sleeve nut 139 and the other end of said helical spring 143 engaging one face of the disk 142.

Exteriorly of the casing 137, the slide member 141 has a lock nut 144 threaded thereto, this lock nut, in the manner hereinafter described, being adapted to coat with the adjacent face of the sleeve nut 140.

Secured to the inner free end of each slide member 141 is an angle member 145, Figs. 3 and 7a, each angle member 145 carrying a plate 146, the lower end of which is slidable on a rod 147 fixed to and projecting horizontally from the associated carriage 135. The horizontal arm of each angle member 145 carries a side gauge roller 148, Fig. 3b, and a guide member 149, this roller and guide member being secured in assembled relation by a bolt 150.

As clearly shown in Fig. 4, a pair of side-by-side, horizontally disposed rods 151, 152, are mounted for free slideable movement in the aforesaid side frames 13. That carriage 137 at the right, Fig. 4, comprises a sleeve extension 137a which is suitably secured to the rod 151, Fig. 9, as by a screw 151a. In generally the same manner, that carriage 137 at the left, Fig. 4, comprises a sleeve extension 137b which is suitably secured to the rod 152, Fig. 9, as by a screw 152a.

As illustrated in Figs. 4 and 7, a collar 153 is suitably secured to the rod 151 and a helical spring 154 encircling said rod 151 is disposed between this collar 153 and an abutment 153a upstanding from and secured to the aforesaid bar 131, Fig. 9. In a similar manner, a collar 155 is suitably secured to the rod 152 and a helical spring 156 encircling said rod 152 is disposed between this collar 155 and an abutment 155a corresponding with the aforesaid abutment 153a ex-

terior to the face of the adjacent sleeve extension 137b.

Referring to Fig. 4, the above described shaft 8 is shown as extending beyond that side frame 1 at the right and as having a cam member 157 secured thereto for rotatable movement therewith. Coactable with this cam member 157 is a roller 158 rotatably secured to one side of a lever 159 terminating in a sleeve extension 160 journaled for free oscillatory movement on a stub shaft 161 carried by a bracket 162 suitably secured to the exterior face of the adjacent side frame 1, Figs. 4 and 6.

The lever 159 terminates in a rack segment 163 disposed in meshing relation with respect to a gear wheel 164 secured to and oscillatory with a vertical shaft 165 journaled in bearings formed in brackets 166 suitably secured to the exterior face of the adjacent side frame 13.

Above the upper bracket 166, the shaft 165 has secured thereto for oscillatory movement therewith a hub 167 which, preferably, forms an integral part of a frame 168 on which a block 169 is horizontally adjustable under the control of a screw 170 journaled in a section of said frame 168, the frame 168 and the block 169 being maintainable in fixed position with respect to each other by a locking screw 171. Upstanding from the block 169 are a pair of spaced, vertical stub shafts 172 on which the respective rollers 173, 174 are journaled. The roller 173 is coactable with a member 175 secured to, projecting laterally from, and movable with the aforesaid rod 151. The roller 174 is coactable with the inner surface of an arcuate member 176 secured to and movable with the aforesaid rod 152.

In view of the description stated above, it will be clear that the screws 151a, 152a shown in Fig. 9 as coacting with the respective rods 151, 152 hold the two casings 137 in facing relation at the respective opposite sides of the sheet-feeding mechanism. These two casings and the associated mechanism are of duplicate construction and, accordingly, it follows that either side of said sheet-feeding mechanism has associated therewith a side gauge which is similar to the side gauge on the other side of the machine.

During operation of the printing press P, the shaft 8 rotates continuously and, in so doing, the cam 157 oscillates the arm 159 whereby, through the described gear arrangement, the vertical shaft 165 and the frame 168 are oscillated. It will be understood that the cam 157 rotates once for each cycle of operation of the printing press P and that the cam is correctly timed with respect to said cycle.

When the high section of the cam 157 is in engagement with the roller 158, the casings 137 are so positioned that they are most closely adjacent each other. At this time, by manipulation of the screws 151a, 152a, said casings 137 may be adjusted longitudinally of the respective rods 151, 152 to cause the outer edges of the respective rollers 148, Fig. 3, to be approximately in gauging position. Then, by manipulation of the respective sleeve nuts 140, the rollers 148 may be set precisely in the desired gauging position, this being determined, of course, by the width of the sheets S which are to be passed to the printing press P by the sheet-feeding mechanism.

In accordance with the invention and as more fully hereinbefore described, the screws 170 and 171 are adapted to maintain the block 169 in either of two positions, Figs. 7 and 8, with respect to the frame 168. In both positions, however,

the rollers 173, 174 are offset in a corresponding manner on the respective opposite sides of the vertical shaft 165.

Referring to Fig. 7, the vertical shaft 165, under the influence of the high section of the cam 157, has just completed movement of the block 169 in a counter-clockwise direction with the result that the rod 151 has been moved from left to right and the rod 152 had been moved from right to left to thereby bring the gauging rollers 148 to their most advanced positions toward each other. This movement is timed to occur as a sheet S is passing along the slats 101 and while said sheet is between said rollers. Accordingly, if the sheet S is misplaced from the course which it should take while passing through the printing press P, one roller 148 or the other engages the side of the sheet and properly positions the same.

Therefore, with the parts positioned as shown in Fig. 7, the low section of the cam 151 is just becoming effective to permit the side gauges to return to their respective non-gauging positions. That is, the block 169 moves clockwise under the control of the compressed springs 154 and 156, the spring 154 moving the rod 151 from right to left and the spring 156 moving the rod 152 from left to right.

In accordance with the invention, one of the gauge rollers 148 should be "locked" so as to be incapable of movement laterally of the sheet-feeding mechanism while the other gauge roller 148 should be capable of movement in such lateral direction against the action of the associated spring 143. When the lock nuts 144 are spaced from the respective sleeve nuts 140, Fig. 7a, both gauge rollers 148 are freely movable laterally of the sheet-feeding mechanism against the action of the associated springs 143. In order to "lock" one of said gauge rollers as specified, it is necessary only to move a lock nut 144 into engagement with the outer surface of the adjacent sleeve nut 140.

When the block 169 is positioned with respect to the frame 168 as shown in Fig. 7, the lock nut 144 carried by the side gauge controlled by the rod 152 should be set against the outer surface of the adjacent sleeve nut 140. The associated gauging roller 148, then, becomes the "fixed" roller whereas the other roller 148 is capable of yielding movement against the action of the associated spring 143.

In accordance with a feature of the invention, the member 176 comprises an arcuate section 176a which, when the parts are positioned as shown in Fig. 7, is concentrically related to the roller 174. Accordingly, during initial movement in a clockwise direction of the block 169, when positioned as shown in Fig. 7, the roller 174 rides along said surface 176a and no receding movement of the aforesaid "fixed" gauging roller 148 occurs. However, as soon as said roller 174 moves beyond the surface 176a, the "fixed" gauging roller 148 starts to recede from its gauging position.

It has been demonstrated in practice that the provision of a temporarily stationary "fixed" gauging roller as described immediately above, particularly when the same is associated with the other resiliently mounted gauging roller, yields highly satisfactory results as regards the alinement of the successive sheets S on their intended path.

In Fig. 8, I have shown the block 169 in its alternate position with respect to the frame 168. As illustrated in Fig. 8, the high section of the

cam 157, Fig. 4, has just completed movement of the block 169 in a counter-clockwise direction and said cam 157 is just becoming effective to permit the side gauges to return to their respective non-gauging positions.

As shown in Fig. 8, the member 175 comprises an arcuate section 175a which is concentrically related to the roller 173 and which has the same function as the above described arcuate section 176a of the member 176. With the block positioned as shown in Fig. 8, the lock nut 144 carried by the side gauge controlled by the rod 151 should be set against the outer surface of the adjacent sleeve nut 140. The associated gauging roller 148, then, becomes "fixed" whereas the other gauging roller 148 should be movable against the action of the associated spring 143.

As well understood in the art, a dampening medium, such as water, acidulated water, or the like, should be applied to the plate cylinder 201a of the printing press as the printing operation proceeds. To this end, as shown in Figs. 1 and 12, the plate cylinder 201a is shown as having secured thereto a gear wheel 201 which meshes with and drives a gear wheel 202, the latter, in turn, meshing with and driving a gear wheel 203, the gear wheel 202 and gear wheel 203 being mounted on the respective shafts 204 and 205 which are journaled in any suitable manner, not shown. The shaft 205 carries a worm 205a which meshes with and drives a worm wheel 206 secured to and rotatable with a drive shaft 207 journaled in the manner hereinafter described.

Suitably secured, as by the bolts 208, to that side frame 13 at the left, Fig. 1, is a gear housing 209. The aforesaid shaft 207 is supported in bearing brackets 210 secured to and supported by the wall structure of said gear housing 209.

Secured to the drive shaft 207 for rotatable movement therewith is a gear wheel 211 meshes with and drives a gear wheel 212 secured to and rotatable with a shaft 213, one end of which is supported in a bearing indicated at 214, Fig. 12a, in the aforesaid side frame 13, the other end of said shaft 213 being suitably supported by a bearing, not shown, carried by the wall structure of the aforesaid gear housing 209.

Secured to and rotatable with the shaft 213 is an eccentric 215 with which coacts a roller 216 carried by one end of an arm 217 having a hub 217a, Fig. 14, mounted for oscillatory movement on the hub 217a of another arm 218. This hub 217a is secured to and oscillatory with a tubular shaft 219 journaled at one end in the aforesaid side frame 13 and, adjacent its other end, in a bearing bracket 220 secured to the aforesaid wall structure of the gear housing 209. The aforesaid arm 217 is suitably biased in a clockwise direction, Fig. 12, as by a helical spring 216a disposed around a rod 216b, one end of which is pivoted to the lower end of said arm 217 and the other end of which is slidable in a bearing block 216c upstanding from the wall structure of the gear housing 209. The spring 216a under compression is confined between the block 216c and a collar secured to said rod 216b. Hence, the arm 217 is biased in a clockwise direction as specified.

The aforesaid arm 217, at the end thereof opposite the roller 216, has fixed thereto a transverse pin 221 which supports a pawl 222 for oscillatory movement, said pawl 222 being biased in a counter-clockwise direction, Fig. 13, under the influence of gravity. The pawl 222 carries a laterally projecting pin 223, Fig. 14, which extends through a slot 224a, Fig. 13, formed in an

arm 224 loosely pivoted on a shaft 225 journaled in the aforesaid side wall 13 and in the wall structure of said gear housing 209, this arm 224 having formed integrally therewith an arm 227 which, at its free end, carries a roller 228 utilizable as hereinafter described. Secured to the shaft 225 for rotatable movement therewith and at the end thereof outside of said side wall 13 is an operating handle 226, Fig. 12, with which is integrally formed an arm 229, Fig. 13, terminating in a hook section 229a utilizable as hereinafter described.

The aforesaid arm 218, on the upper surface thereof, is provided with a transverse groove 218b, this groove being adapted to receive the operative end of the pawl 222. Projecting laterally from and fixed to the arm 218 is a pin 230 with which the aforesaid hook section 229a of the arm 229 is adapted to coat.

The above described tubular shaft 219 should be biased in a clockwise direction, Figs. 12 and 14, and to this end there may be utilized a suitable helical spring 231, one end of which is fastened to an arm 232 secured to and oscillatory with said tubular shaft 219, the other end of the spring 231 being fastened to the wall structure of the gear housing 209, Fig. 12.

Extending axially through the tubular shaft 219 is a control rod 233, Fig. 14, which, exteriorly of the aforesaid side wall 13, carries an actuating handle 234 utilizable as hereinafter described, said handle 234 preferably carrying a manually operable screw 235, the operative end of which is adapted to engage a segment 236 secured to the adjacent surface of said side wall 13. The control rod 233, at its end remote from the handle 234, has a worm 237 secured thereto for oscillatory movement therewith, this worm 237 meshing with and operating a nut member 238 secured to a sleeve 239, the inner surface of which carries a plurality of rollers 240 coactable with the wall surface of a groove 219a formed circumferentially in the tubular shaft 219. The remote end of the control rod 233 is disposed and rotates in a cup housing 241 which is bolted or otherwise suitably secured to the wall structure of the aforesaid gear housing 209.

Mounted on the aforesaid tubular shaft 219 is the hub 242a of a cam member 242, said hub 242a having secured thereto an inwardly projecting key or pin 243 which rides in and is controlled by a slot 219b formed spiral-fashion in said tubular shaft 219.

Coactable with the cam face of the cam member 242 is a roller 244 rotatable on one end of an arm 245 secured to and oscillatory with a shaft 246 mounted in bearings carried by the wall structure of the aforesaid gear housing 209. As shown in Fig. 12, the upper end of the arm 245 has pivoted thereto a rod 247 which extends freely through a bearing block 248 carried by the wall structure of said gear housing 209. The rod 247, at its free end, may carry a nut 249 and, further, said rod 247 should be encircled by a helical spring 250 which is maintained under compression between the aforesaid block 248 and a washer secured in fixed position on the rod 247. Accordingly, the spring 250 biases the arm 245 in a counter-clockwise direction, Fig. 12.

Secured to and oscillatory with the opposite ends of the shaft 246 are the respective upstanding, bearing supports 253 which, in a manner known to the art, serve as a bearing means for the shaft 254 of a ductor roller 255. As hereinafter described, the ductor roller 255 is adapted to re-

ceive a film of a dampening medium from a fountain roller 256, the shaft 257 of which is rotatably supported in bearing brackets 258 suitably secured to the wall structure of said gear housing 209, the lower surface of said fountain roller 256 moving through the dampening medium contained in a fountain receptacle 259. As stated, the ductor roller 255 receives the dampening medium from the fountain roller 256 and the dampening medium thus received, in turn, is transferred to the rollers 260, 261, these rollers being suitably supported for rotatable movement and the roller 261 transferring a film of said dampening medium directly to the aforesaid plate cylinder 281a.

The hereinbefore described shaft 267 has a bevel gear 262 secured to that end thereof opposite the worm wheel 206. The bevel gear 262 meshes with and drives a corresponding bevel gear 263 secured to and rotatable with a vertical shaft 264 mounted in a lower bearing 265 and in an upper bearing, not shown, these bearings being suitably secured to the wall structure of the gear housing 209. Secured in suitable spaced relation and rotatable with the shaft 264 are a plurality of gear wheels 266, 267, 268, these gear wheels having different diameters, respectively, and being utilizable as hereinafter described.

Secured in spaced bearing sleeves 269 and 270 which, in suitable manner, are carried by the wall structure of said gear housing 209 is a sleeve shaft 271, Fig. 12a, which, at its upper end, carries a bevel gear 272 disposed in meshing relation with respect to a corresponding bevel gear 273 secured to and rotatable with the aforesaid shaft 257 for the fountain roller 256, this shaft 257, if desirable and necessary, comprising a coupling 257a, in Fig. 12a, manually operable to permit removal of said fountain roller 256 without disturbing the gear connection 72, 73. Slidable within the sleeve shaft 271 is a control rod 274 which is formed with a vertical slot 274a through which is adapted to extend the nose 275a of a pawl 275 pivoted in a vertical, slotted section of said control rod 274. As hereinafter described, the pawl 275 is adapted to lock any one of three gear wheels 276, 277, 278 to the sleeve shaft 271, these gear wheels last named, normally, being freely rotatable on said sleeve shaft 271 and maintained in suitable spaced relation by spacing collars as shown. The control rod 274, at its lower end, has a grooved collar 279, Fig. 12, secured thereto for rotatable movement therewith. Operatively related to this collar 279 is an arm 280 secured to and oscillatory with a shaft 281 journaled in the aforesaid side frame 13, said shaft 281, at its outer end, carrying an actuating arm 282.

The hereinbefore described shaft 264, Fig. 12a, adjacent its lower end, has secured thereto a pair of spaced gear wheels 283, 284. Secured interiorly of the gear housing 209, in one lower corner thereof, is a bearing bracket 285 in which a vertical shaft 286 is suitably journaled. Loosely mounted in spaced relation on the shaft 286 are a pair of cam disks 287, 288. A pair of spaced gear wheels 289 and 290 are loosely mounted on the shaft 286 and the gear wheels last named continuously meshing with the aforesaid gear wheels 283 and 284, respectively. Each of the gear wheels 289, 290 comprises a hub 291 and each hub 291, as shown in Fig. 15, is provided with a pawl-receiving groove 291a. Pivoted to each cam disk 287, 288 is a pawl 292 and the operative end of each pawl 292 is adapted to en-

gage with the adjacent groove 291a. Suitably secured to each cam disk 287, 288 is a leaf spring 293 and each of these leaf springs 293 coacts with the adjacent pawl 292 so as to bias the same in a direction toward the associated pawl-receiving groove 291a.

As shown in Fig. 12a, the aforesaid side frame 13 is provided with a pair of inwardly-facing bearing recesses 294, 294, these recesses receiving the respective rods 295, 296 which are adapted to coact with the aforesaid pawls 292, respectively, each of said rods 295, 296 having associated therewith a helical spring 297 utilizable for biasing the respective rods 295, 296 from left to right, Fig. 12a.

Mounted for oscillatory movement in the aforesaid side frame 13 is a shaft 298 which, exteriorly of said side frame, carries an operating handle 299 having associated therewith a locking screw 300. The shaft 298, on its inner end, has secured thereto a member 301, provided with a pair of arcuate slots 301a, 301a through which extend the respective rods 295, 296. Each of the rods last named comprises a flanged section 302, Fig. 15, these flanged sections 302 being utilizable for limiting movement of the respective rods 295, 296 in a direction toward the right, Fig. 12a.

The operation of the mechanism disclosed in Figs. 12, 12a, 13, 14 and 15 is as follows:

Power from the gear wheel 201 carried by the plate cylinder 201a is transmitted through the gear wheel 202 and worm wheel 203 to the worm wheel 206 carried by the shaft 207. Accordingly, the shaft 207 rotates the shaft 264 through the mechanical connection between said shafts 207, 264 constituted by the bevel gears 262 and 263.

As hereinbefore stated, the gear wheels 266, 267 and 268 are secured to the shaft 264 for rotatable movement therewith. These gear wheels last named, during rotation of the shaft 264, continuously rotate the gear wheels 276, 277 and 278. With the arrangement shown, the gear wheels 277, 278 of the group of gear wheels last named idle on the sleeve shaft 271. The gear wheel 276, however, is engaged by the nose 275a of pawl 275 and, therefore, said gear wheels 276 is locked to the sleeve shaft 271. It results, therefore, that power is transmitted from the shaft 264 to the sleeve shaft 271 by way of the gear wheels 266, 276. From the sleeve shaft 276, power is transmitted to the shaft 257 of the fountain roller 256 through the mechanical connection afforded by the bevel gears 272, 273. From a consideration of Fig. 12a, it will be obvious, due to the diametrical variation between the gear wheels 266 and 276, that the fountain roller 256 rotates at relatively slow speed.

If it becomes desirable for the fountain roller 256 to rotate at a faster speed, the operator moves the arm 282 in a counter-clockwise direction, Fig. 12, to thereby lower the control rod 274 and transfer the actuating nose 275a of the pawl 275 from the gear wheels 276 to the gear wheel 277. With this arrangement, power is transmitted from the shaft 264 to the sleeve shaft 271 through the gear wheels 267, 277.

In case it becomes desirable for the fountain roller 256 to rotate at a still faster speed, the operator moves the arm 282 further in a counter-clockwise direction, Fig. 12, to thereby again lower the control rod 274 and moves the nose 275a of the pawl 275 from the gear wheel 277 to the gear wheel 278. With this arrangement, power is transmitted from the shaft 264 to the sleeve shaft 267 through the gear wheels 268, 278. 75

The gear wheel 211, which rotates continuously under the control of the shaft 207, effects rotation of the gear wheel 212 and the latter, in turn, rotates the eccentric 215. Therefore, the arm 217 is oscillated continuously by engagement of the eccentric 215 with the roller 216.

The pawl 222, which is carried by the arm 218, has the end thereof seated in the groove 218b of the arm 218. Inasmuch as the hub 218a of said arm 218 is keyed to the tubular shaft 219, it results that the above noted oscillation of the arm 217 causes said tubular shaft 219 to move in a rotatable manner first in one direction and then in the other. The hub 242a of the cam member 242 is secured to the tubular shaft 219 by the key 243. Hence, the described oscillation of the tubular shaft 219 effect oscillatory movement of the cam member 242 in the directions indicated by the arrow, Fig. 12.

The cam member 242 comprises a low section 242c and a high section 242d. When the roller 244 carried by the lower end of the arm 245 is in engagement with the low section 242c of said cam member 242, the spring 250 holds the ductor roller 255 in engagement with the roller 260. When said roller 244 is in engagement with the high section 242d of said cam member 242, the ductor roller 255 is held in engagement with the fountain roller 256 against the force of the spring 250. From the foregoing, it follows that oscillation of the cam member 242 produces oscillation of the ductor roller 255 which first engages the fountain roller 256 and then engages the roller 260.

As the parts are shown on the drawings, the arrangement is such that the high section 242d of the cam member 242 is effective for a relatively long period to hold the ductor roller 255 in engagement with the fountain roller 256. In case it becomes desirable to shorten the period while these two rollers are in engagement, the operator moves the handle 234 from right to left, Fig. 12, and then actuates the screw 235 to lock the same in a desired position. In so doing, by the described mechanical connection shown in Fig. 14, the tubular shaft 219 is moved from right to left, Fig. 14, and, by the wall surface of the slot 219b, the cam member 242 is moved to a desired degree in a clockwise direction, Fig. 12. Accordingly, during continued operation of said cam member 242, the roller 255 dwells for a desired shorter period on the fountain roller 256 and for a longer period on the roller 260.

In case it becomes desirable to hold the ductor roller 255 permanently in engagement with the roller 260, the operator applies pressure to the handle 226 in a clockwise direction, Fig. 12, whereby the arm 229 is moved in the same direction, Figs. 12 and 13. Accordingly, the next time that the arm 218 reaches its position at the right, Fig. 13, the pressure thus applied to the handle 226 causes the hook section 229a to clear the pin 230. Therefore, the arm 229 rises to its full extent and, in so doing, engages the pin 223 which is carried by the pawl 222. In this manner, the pawl 222 is disengaged from the arm 218 and the cam member 242 remains in its position at the right, Fig. 12. Under these circumstances, the spring 250 holds the ductor roller 255 against the roller 260.

When it becomes desirable to resume oscillation of the roller 255, the handle 226 is moved in a counter-clockwise direction, Fig. 12, to permit the pawl 222 to resume operative relation with the arm 218. As a result, oscillation of the tubular shaft 219 and the cam member 242 is resumed.

The hereinbefore described shaft 264 rotates continuously during operation of the printing press P and, by the gear wheels 283 and 284, produces continuous rotative movement of the respective gear wheels 289, 290, which, as stated, are loose on the shaft 286. With the handle 299 in the position shown, Fig. 12, the rods 295, 296 are held by the respective springs 297 in their advanced positions toward the right, Fig. 12a. When thus positioned, the rods 295, 296 engage the respective pawls 292 and hold them, against the action of the associated springs 293, in such position that they do not engage the respective pawl-receiving grooves 291a. Accordingly, when said handle 299 is positioned as shown in Fig. 12, the cam disks 287, 288 remain stationary during rotation of the shaft 264.

If the handle 299 is swung in a counter-clockwise direction, Fig. 12, approximately one-half of its arc of movement, the upper slot 301a of the member 301 coacts with the rod 295 to move the same from right to left, Fig. 12a. In so doing, the associated pawl 292 is released to thereby connect the cam disk 287 to the rotating gear wheel 289.

The diametrical relation of the gear wheels 283, 289 is such, for example, that the gear wheel 283 rotates twice through an angle of 360 degrees while the gear wheel 289 is rotating once through an angle of 360 degrees. Furthermore, the gear trains included in the driving connection for the shaft 264 are of such character that said shaft 264 rotates through an angle of 360 degrees during one complete cycle of the printing press P. Accordingly, it follows that the cam disk 287 rotates through an angle of 360 degrees during two cycles of said printing press P.

When the cam disk 287 is actuated to rotate as described above, the high section thereof shown in Fig. 15 engages the roller 228 to thereby swing the arms 224, 227 in a clockwise direction, Figs. 12 and 13. Accordingly, by the pin 223, the pawl 222 is elevated and disengaged from the arm 218. When this happens, the spring 250, acting through the described mechanism, becomes effective to swing the ductor roller 255 in a counter-clockwise direction, Fig. 12, and hold the same against the adjacent roller 260.

As oscillatory movement of the pawl 222 continues under the control of the arm 217, the aforesaid high section of the cam disk 287 remains in engagement with the roller 228. Accordingly, the first time that the pawl 222 again comes into coinciding relation with the groove 218b of the arm 218, the end of said pawl 222 is retained in its elevated position and, as a result, the ductor roller 255 remains in engagement with the roller 260.

However, the second time that the end of the pawl 222 comes into coinciding relation with said groove 218b of the arm 218, the cam disk 287 has rotated to such extent that the low section thereof is in engagement with the roller 228. Accordingly, the arms 224, 227 are free to assume the position thereof shown in Fig. 13 and such position is taken when said pawl 222 comes into the position last described, the end of the pawl 222 dropping into said groove 218b at this time.

When this happens, the ductor roller 255 is caused to retreat from the roller 260, move into engagement with the fountain roller 256 and then retreat from the latter. Assuming that the handle 299 remains in the position last described, the high section of the cam disk 287, during continued operation of the printing press, again engages the roller 228 and the operation described

above is repeated. In this manner, the ductor roller 255 is caused to engage the roller 260 in the normal manner as described above under the control of cam member 242 and, in addition, to remain in engagement therewith during one complete cycle of the printing press P.

If the handle 299 is swung in a counter-clockwise direction, Fig. 12, to the full extent of its arc of movement, the upper slot 301a of the member 301, by reason of the curvature of said slot 301a, releases the rod 295 so that the same moves from left to right, Fig. 12a, under the control of its associated spring 297. As a result, the associated pawl 292 is engaged by said rod 295 to thereby cause the cam disk 287 to be disconnected from the rotating gear wheel 289. As an added result of the last described movement of handle 299, the lower slot 301a of the member 301 coacts with the rod 296 to move the same from right to left, Fig. 12a. In so doing, the associated pawl 292 is released to thereby connect the cam disk 288 to the rotating gear wheel 290.

The diametrical relation of the gear wheels 284, 290 is such, for example, that the gear wheel 284 rotates three times through an angle of 360 degrees while the gear wheel 290 is rotating once through an angle of 360 degrees. Accordingly, it follows that the cam disk 288 rotates through an angle of 360 degrees during three cycles of said printing press P.

When the cam disk 288 is actuated to rotate as described above, the high section 288a thereof shown in Fig. 15 engages the roller 228 to thereby swing the arms 224, 227 in a clockwise direction, Figs. 12 and 13. Accordingly, in the manner hereinbefore described, the spring 250 becomes effective to swing the ductor roller 255 in a counter-clockwise direction, Fig. 12, and hold the same against the adjacent roller 260. The ductor roller 255 remains in the position last described during two cycles of oscillatory movement of the pawl 222 because, in this instance, the high section 288a of the cam disk 288, which is substantially longer than the high section of the cam disk 287, prevents the end of the pawl 222 from engaging the groove 218b of the arm 218. However, the third time that the end of the pawl 222 is in coinciding relation with said groove 218b of the arm 218, the cam disk 288 has rotated to such extent that the low section thereof is in engagement with the roller 228. Accordingly, the arms 224, 227 are free to assume the position thereof shown in Fig. 13 and such position is taken when said pawl 222 comes into the position last described, the end of the pawl 222 dropping into said groove 218b at this time.

When this happens, the ductor roller 255 is caused to retreat from the roller 260, move into engagement with the fountain roller 256 and then retreat from the latter. Assuming that the handle 299 remains in the position last described, the high section 288a of the cam disk 288, during continued operation of the printing press, again engages the roller 228 and the operation described above is repeated. In this manner, the ductor roller 255 is caused to engage the roller 260 in the normal manner as described above under the control of cam member 242 and, in addition, to remain in engagement therewith during two complete cycles of the printing press P.

In view of the foregoing, it follows that the operator, by the simple act of manually moving the handle 299, may cause the ductor roller 255 to skip engagement with the fountain roller 256

either once or twice as desired. A control of this character is highly desirable in connection with the application of the dampening medium to the printing press assembly.

It shall be understood that the invention is not to be limited to the precise arrangement described above. Obviously, the number of times which the ductor roller 255 skips engagement with the fountain roller 256 may be varied as desired and, furthermore, it will be understood that the control effected by the cam disks 287, 288 need not be timed precisely with the operation of the printing press.

Side gauge mechanism of the character hereinbefore disclosed yields satisfactory results. However, in accordance with the invention, I have devised side gauge mechanism of a preferred modified type and the same is illustrated in Figs. 10 and 11 wherein a horizontal structure 310 is shown as extending transversely between the aforesaid side frames 13, said structure 310 being secured to said side frames 13 in any suitable manner, not shown. This structure 310, at the side thereof adjacent the printing cylinders, comprises an upper track member 310a extending entirely across the machine. The structure 310, at the side thereof removed from said printing cylinders and adjacent the respective side frames 13, comprises a plurality of upwardly extending supports 310b to which, as by the bolts 311, the respective track members 312 are secured, each track member 312 terminating adjacent a side frame 13 and extending only part way across the machine.

Adjacent each side of the machine, the aforesaid track member 310a and the associated track member 312 slidably support a structure 313. In accordance with the invention, the structures 313 are adjustable toward or from each other along their respective track members and, to this end, each of said structures 313 may be provided with an internally threaded, horizontal passage 313a into which is threaded a lead screw 314, each lead screw 314 extending through and being journaled in the adjacent side frame 13 and, exteriorly of the latter, carrying a hand wheel 315.

Referring to Fig. 10, the hereinbefore described shaft 8, exteriorly of the adjacent side frame 1, is shown as having a bevel gear 316 secured thereto for rotatable movement therewith, this bevel gear meshing with and driving a bevel gear 317 secured to and rotatable with one end of a shaft 318 journaled in a bearing 319 secured to and projecting from the exterior surface of the adjacent side frame 1, said shaft 318 having another bearing, not shown, secured to and projecting from the adjacent side frame 13. The shaft 318, at its end removed from the bevel gear 317, has secured thereto a worm wheel 320 which meshes with and drives a worm wheel 321 secured to and rotatable with a horizontal shaft 322 journaled in bearings formed by the aforesaid side frames 13 and in a bearing 323 upstanding from the aforesaid structure 310 at the mid-section thereof. The shaft 322, at opposite sides of the bearing 323, is provided with a series of longitudinally extending slots 322a which terminate adjacent said bearing 323. By virtue of these slots 322a, the shaft 322 is splined to a pair of spaced worm wheels 324 disposed, respectively, in the structures 310. Each worm wheel 324 is rotatable in a chamber formed in the structure 313, such chamber being defined, in part, by the thrust bearings 325.

Each worm wheel 324 meshes with and drives

a worm wheel 326 carried by and rotatable with a vertical shaft 327, these shafts 327 having upper and lower needle bearings in the respective structures 313.

- 5 That vertical shaft 327 at the right, Figs. 10 and 11, has secured thereto for rotatable movement therewith the hub 328a of a disk 328 which, on its lower surface, is provided with a downwardly facing eccentric channel 328b adapted to receive a ring 329 of corresponding eccentric shape. After the eccentric ring 329 has been positioned in its channel 328b as shown in Fig. 11, a circular guide ring 330 is disposed around the outer surface of said ring 329 and suitably retained thereto, as by friction between the interengaging surfaces. Thereafter, a lower guide ring 331 is placed in position as shown and, by bolts 332, or equivalent, the disk 328, the ring 329 and the ring 331 are retained in assembled relation.
- 10 As shown in Fig. 11, the rings 329, 331 are so formed that the respective outer surfaces thereof are flared in opposite directions. In addition, these rings 329, 331 are so spaced that the sheets S, as they pass toward the printing zone, may 15 freely engage the outer surface of the ring 329.

That vertical shaft 327 at the left, Figs. 10 and 11, has secured thereto for rotatable movement therewith a collar 333 which comprises a pair of oppositely facing stems 333a disposed transversely of the machine. Slidably associated with these pin supports 333a is the hub 334a of a disk 334 which, on its lower surface, is provided with a downwardly facing eccentric channel 334b adapted to receive a ring 335 of corresponding eccentric shape. After the ring 335 has been positioned in its channel 334b, a circular guide ring 336 is disposed around the outer surface of said ring 335 and suitably retained thereto, as by friction between the interengaging surfaces. Thereafter, a lower guide ring 337 is placed in position as shown and, by bolts 338, or equivalent, the disk 334, the ring 335 and the ring 337 are retained in assembled relation.

The spacing between the rings 336, 337 should 45 correspond with the spacing between the hereinbefore described rings 330, 331 and, further, the ring 337 should be recessed around the upper part of the structure 310 as indicated at 337a so as to permit movement transversely of the machine of the disk 334 and associated parts as hereinafter more fully described.

The above described hub 334a of the disk 334 is maintained in operative relation with respect to the stems 333a by a cover plate 339 which, 55 by screws 340, is secured to said hub 334a. It will be understood, therefore, that the passages which slidably receive the respective stems 333a are defined by surfaces of the hub 334a and the cover plate 339.

- 60 The aforesaid hub 334a comprises an upstanding standard 333b and the cover plate 339 likewise comprises an upstanding standard 339a, these standards being disposed in alignment transversely of the machine and the standard 339a carrying a horizontally disposed bearing sleeve 341. A rod 342 pivoted to the standard 333b is slidably received in the sleeve 341 and the free end of said rod 342 carries a nut 343 coactable with the end of said sleeve 341. Carried by the rod 342 is a helical spring 344 which biases the hub 334a and the parts carried thereby in a direction from left to right, Fig. 11.
- 65
- 70

Preferably, in accordance with the invention, 75 each of the aforesaid structures 313 comprises

a U-shaped extension 313b, these extensions 313b projecting in opposite directions toward the respective side frames 13, Fig. 10, and overlying the respective sets of track members 310a, 312. As shown particularly in Fig. 11, a member 345 is disposed beneath the cross-section of each U-extension 313b and each of the members 345 has fixed thereto a bolt 346 which extends upwardly between the adjacent track members 310a, 312 and through said U-extension cross-section above which said bolt 346 carries a nut 347.

As indicated in Fig. 10, it is desirable for that lead screw 314 at the left to have secured thereto a disk 348 bearing suitable scale marks with which coact a pointer 349 suitably secured to the adjacent side frame 1.

The operation of the side gauge mechanism illustrated in Figs. 10, 11 and 11a is as follows:

The power obtained from the shaft 8 by way of the bevel gears 316, 317 effects rotation of the shaft 318 which, by the worm wheels 320 and 321, produces rotation of the shaft 322. The worm wheels 324 are rotated by the shaft 322 and said worm wheels 324, in turn, rotate the respective worm wheels 326 by which the vertical shafts 327 are rotated, respectively.

That shaft 327 at the right, Fig. 11, effects rotation in a counter-clockwise direction, Fig. 10, of the disk 328 and the members secured thereto as hereinbefore described. That shaft 327 at the left, Fig. 11, effects rotation in a clockwise direction, Fig. 10, of the disk 334 and the members secured thereto as hereinbefore described.

The side gauge mechanism is shown in Fig. 10 in normal gauging relation. That is, the gauging section 329a of the eccentric ring 329 and the gauging section 335a of the eccentric ring 335 face each other. As the shaft 322 rotates, these rings 329 and 335 rotate in unison and adjust the position of the sheets S laterally of the machine in the manner hereinafter described. The timing is such that the rings 329, 335 rotate through an angle of 360 degrees each time that the sheet-feeding mechanism feeds a sheet S along the slats 101.

With the parts positioned as shown in Fig. 10 and with the nuts 247 loosened, the operator may adjust the hand wheels 315 to move the structures 313 either toward or from each other along the respective sets of track members 310a, 312. In so doing, the aforesaid gauging sections 329a, 335a are spaced apart a distance corresponding with the width of the sheets S to be fed to the printing press P by the sheet-feeding mechanism.

Having established the approximate adjustment just described, the operator may rotate the nut 343 to move the disk 334 and the thereby-carried ring 335 a small distance either toward or from the ring 329. In this manner, the gauging sections 329a, 335a may be spaced apart a distance corresponding exactly with the width of the sheets S to be fed to the printing press P. When this has been done, the nuts 347 are tightened to positively retain the side gauges in their proper adjusted positions.

After the adjustment last described has been effected, the disclosed mechanism may be placed in operation to feed the sheets S in succession from the stack thereof to the printing press P. As each sheet S passes along the slats 101 under the control of the fingers 96, the forward edge thereof approaches the two side gauges disclosed in Figs. 10 and 11. If any sheet S is displaced to one side or the other laterally of the proper

path therefor, the side of that sheet comes into engagement either with the rotating ring 329 or with the rotating ring 335. As a result, said sheet, at least at its forward edge, is shifted side-wise onto the course which it is to take as it passes into engagement with the printing cylinders. As movement of the sheet continues, the gauging sections 329a, 335a take the position illustrated in Fig. 10 whereby the entire area of the sheet is centered onto its intended course. It will be noted that the spring 344 biases the disk 334 toward the right, Fig. 11. This spring 344, therefore, serves as a resilient mounting for the side gauge at the left, Figs. 10 and 11, so that the same may yield slightly under the impulse of the sheet S being gauged, if that becomes necessary.

Side gauge mechanism of the character discussed above is of special value in high speed operation. The gauging action is effected by a "rolling" contact between the gauging rings and the sheet. This is superior to the impact gauging effected by reciprocating gauges which, when operated at high speed, are apt to "bounce" the sheet. Further, side gauge mechanism of the character disclosed in Figs. 10 and 11 is simple to construct, operate and repair if that becomes necessary.

It will be understood by those skilled in the art that the utilization of the hereinbefore described magnetic rollers 112 requires the sheets S to be formed of suitable magnetic material, such as iron. However, the invention is not to be thus limited because, for any type of sheets S, whether formed from magnetic or non-magnetic material, it shall be understood that the herein disclosed magnetic rollers 112 and associated fingers 119 may be omitted and that there may be substituted therefor any other equivalent feeding mechanism such, for example, as of the character disclosed in Recht application Serial No. 151,090, filed June 30, 1937, for feeding sheets to the reciprocating mechanism by which they are advanced to the coating rollers.

Although the feeding mechanism comprising the chains 58, 58a and associated apparatus has been described as utilizable for feeding sheets of material to a printing press, it shall be understood that the invention is not to be thus limited. Thus, for example, such feeding mechanism may be utilized, for example, to feed sheets of material to a coating machine such as disclosed in my pending application Serial No. 138,512, filed April 23, 1937.

In the appended claims, I have referred to the endless chains which are utilizable for feeding sheets of material toward the cylinder assembly. It shall be understood that these references in the claims to "endless chains" are to be construed as generically descriptive of chains of known construction as well as other equivalent flexible structures of the endless type.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. Mechanism for feeding sheets toward an

assembly comprising a pair of cylinders, said mechanism comprising endless chains disposed, respectively, in parallel vertical planes and having their upper spans extending substantially horizontally toward said cylinders, means on which said chains are mounted, means for operating said chains, means carried by said chains for engagement with the rear surface of each sheet whereby sheets are fed in succession toward said cylinders, and means for decreasing the speed of said last named means as it comes into sheet-engaging position.

2. Mechanism for feeding sheets toward an assembly comprising a pair of cylinders, said mechanism comprising endless chains disposed, respectively, in parallel vertical planes and having their upper spans extending substantially horizontally toward said cylinders, means on which said chains are mounted, means for operating said chains, means carried by said chains for engagement with the rear surface of each sheet whereby sheets are fed in succession toward said cylinders, and means for increasing the speed of each sheet as the front edge thereof arrives at said assembly.

3. Mechanism for feeding sheets toward an assembly comprising a pair of cylinders, said mechanism comprising endless chains disposed, respectively, in parallel vertical planes and having their upper spans extending substantially horizontally toward said cylinders, means on which said chains are mounted, means for operating said chains, means carried by said chains for engagement with the rear surface of each sheet whereby sheets are fed in succession toward said cylinders, means for increasing the speed of each sheet as the front edge thereof arrives at said assembly, and means for immediately thereafter decreasing the speed of each sheet.

4. Mechanism for feeding sheets toward an assembly comprising a pair of cylinders, said mechanism comprising endless chains disposed, respectively, in parallel vertical planes and having their upper spans extending substantially horizontally toward said cylinders, means on which said chains are mounted, means for operating said chains, pusher assemblies carried by the respective chains and comprising upwardly extending sheet-engaging fingers alined transversely of the path of sheet movement, and means for tilting said fingers either forwardly or rearwardly during horizontal movement thereof to increase or decrease the speed of the sheets moved thereby.

5. Mechanism for feeding sheets toward an assembly comprising a pair of cylinders, said mechanism comprising endless chains disposed, respectively, in parallel vertical planes and having their upper spans extending substantially horizontally toward said cylinders, means on which said chains are mounted, means for operating said chains, pusher assemblies carried by the respective chains and comprising upwardly extending sheet-engaging fingers alined transversely of the path of sheet movement, said fingers engaging the rear surface of each sheet in succession to thereby feed the sheets toward said assembly, and means operative as the front edge of each sheet arrives at said assembly for tilting said fingers forwardly, then holding them substantially in vertical position for an interval and then tilting them rearwardly.

6. Mechanism for feeding sheets toward the impression and blanket cylinders of a printing press, said mechanism comprising endless chains

disposed, respectively, in parallel vertical planes and having their upper spans extending substantially horizontally toward said cylinders, means on which said chains are mounted, means for operating said chains in timed relation with respect to said cylinders, means carried by said chains for engagement with the rear surface of each sheet whereby sheets are fed in succession toward said cylinders, and means for increasing the speed of each sheet to move the front edge thereof into engagement with the gripper fingers of said impression cylinder.

7. In combination, an assembly comprising a pair of cylinders between and by which sheets are fed in succession, means timed with said cylinders for feeding sheets in succession toward said assembly, means for applying power to said assembly and to said feeding means whereby sheets are fed in succession toward and then between said cylinders, and means for adjusting said feeding means to thereby feed sheets of different lengths toward said assembly, said adjusting means being operable during the application of power to said assembly and to said feeding means.

8. In combination, an assembly comprising a pair of cylinders between and by which sheets are fed in succession, means timed with said cylinders for feeding sheets in succession toward said assembly, means for applying power to said assembly and to said feeding means whereby sheets are fed in succession toward and between said cylinders, means for adjusting said feeding means to thereby feed sheets of different lengths toward said assembly, means for increasing the speed of each sheet as the front edge thereof arrives at said assembly, and means for changing the position of said last named means in accordance with the adjustment of said feeding means.

9. In combination, an assembly comprising a pair of cylinders between and by which sheets are fed in succession, means timed with said cylinders for feeding sheets in succession toward said assembly, means for applying power to said assembly and to said feeding means whereby sheets are fed in succession toward and then between said cylinders, said feeding means comprising endless chains disposed, respectively, in parallel vertical planes and having their upper spans extending substantially horizontally toward said cylinders, means on which said chains are mounted, and means for adjusting said chains to thereby feed sheets of different lengths toward said assembly.

10. In combination, an assembly comprising a pair of cylinders between and by which sheets are fed in succession, means timed with said cylinders for feeding sheets in succession toward said assembly, means for applying power to said assembly and to said feeding means whereby sheets are fed in succession toward and between said cylinders, said feeding means comprising endless chains disposed, respectively, in parallel vertical planes and having their upper spans extending substantially horizontally toward said cylinders, means on which said chains are mounted, and means for adjusting said chains to thereby feed sheets of different lengths toward said assembly, said adjusting means being operable during the application of power to said assembly and to said feeding means.

11. In combination, an assembly comprising a pair of cylinders between and by which sheets are fed in succession, means timed with said cylinders for feeding sheets in succession toward

said assembly, means for applying power to said assembly and to said feeding means whereby sheets are fed in succession toward and then between said cylinders, said feeding means comprising endless chains disposed, respectively, in parallel vertical planes and having their upper spans extending substantially horizontally toward said cylinders, means on which said chains are mounted, a cam for changing the speed of each sheet as the front edge thereof arrives in the vicinity of said assembly, means for adjusting said chains to thereby feed sheets of different lengths toward said assembly, and means for changing the position of said cam.

12. In combination, an assembly comprising a pair of cylinders between and by which sheets are fed in succession, means timed with said cylinders for feeding sheets in succession toward said assembly, means for applying power to said assembly and to said feeding means whereby sheets are fed in succession toward and then between said cylinders, said feeding means comprising endless chains disposed, respectively, in parallel vertical planes and having their upper spans extending substantially horizontally toward said cylinders, means on which said chains are mounted, a cam for changing the speed of each sheet as the front edge thereof arrives in the vicinity of said assembly, means for adjusting said chains to thereby feed sheets of different lengths toward said assembly, and means for changing the position of said cam, both of said last named means being simultaneously operable during the application of power to said assembly and to said feeding means.

13. Sheet-feeding mechanism comprising a support for a sheet of material, magnetic roller means disposed below said support, means for elevating said magnetic roller means into engagement with said sheet, and means for continuously rotating said roller means to impart translatory movement to said sheet.

14. Sheet-feeding mechanism comprising a support for a sheet of material, stop means engaged by the forward edge of said sheet, magnetic roller means disposed below said support, means for elevating said magnetic roller means into engagement with said sheet, means for disengaging said stop means from said sheet at about the time the latter is engaged by said magnetic roller means, and means for continuously rotating said roller means to impart translatory movement to said sheet.

15. The combination with means for feeding sheets in succession along a path, of side gauge mechanism for adjusting the position of said sheets while they move along said path, said mechanism comprising eccentric devices adapted to be engaged by the respective opposite sides of each sheet as it passes along said path, and means for rotating said eccentric devices in timed relation.

16. The combination with means for feeding sheets in succession along a path, of side gauge mechanism for adjusting the position of said sheets while they move along said path, said mechanism comprising eccentric devices adapted to be engaged by the respective opposite sides of each sheet as it passes along said path, and means for rotating each eccentric device through an angle of 360 degrees as each sheet passes therebetween.

17. The combination with means for feeding sheets in succession along a path, of side gauge mechanism for adjusting the position of said sheets while they move along said path, said mechanism comprising eccentric devices adapted to be engaged by the respective opposite sides of each sheet as it passes along said path, and means for rotating said eccentric devices in timed relation, each of said eccentric devices comprising an eccentric ring having clamping plates secured to the respective opposite sides thereof.

MORRIS LIPTON.
